RAZOR

Neil Holsclaw, Chicago, Ill., assignor of one-half
to Fred E. Sudlow, Rock Island, Ill.

Application July 16, 1938, Serial No. 219,620

2 Claims. (Cl. 30—43)

This invention relates to improvements in mechanized shavers and more particularly to the heads thereof. The main objects of this invention are to provide such a head of improved construction and design; to provide a head which will be adapted positively to shear in a single sweep of the razor all of the hairs on the surface operated upon; to provide a mechanism of this type with a bearing face formed and adapted to raise and hold erect the hairs to be sheared in a position thus provided for, such as to facilitate and assure that they will be sheared close to the skin; to provide a durable mechanism of this character wherein a plurality of operatively succeeding shear edges are employed; to provide in a razor mechanism of this character means to support a series of rows of shear cutters in effective position and especially in staggered relation to one another; to provide in a shear head a plurality of rows of shear couples arranged and actuated to follow in a single sweep of the head one row after another with successive shear couples in mutually offset relation; to provide and organize a face bearing stator and cooperating oscillator, having shear couples arranged staggerwise in effectively successive rows extending crosswise of general shaver movement; and to provide a pair of relatively slideable shear members of this kind in effective relation to each other and to a driving means.

These and other objects will be apparent from the description, drawings, and claims hereinafter set forth.

This invention in several forms is illustrated by the accompanying drawings in which:

Figure 1 is a view, partly in cross-section, of one form (first) of my improved razor head in position on a support.

Fig. 2 is an enlarged top plan view thereof, the middle part of the face plate being broken away and showing the movable cutter.

Fig. 3 is a further enlarged cross-sectional view taken on the line 3—3 of Fig. 2.

Fig. 4 is a still further enlarged fragmentary perspective view, partly in section, of the fixed member of my improved razor shear head.

Fig. 5 is a top plan view of a modified (second) form of shear head construction, enlarged substantially as in Figure 2.

Fig. 6 is a greatly enlarged fragmentary perspective view of the device shown in Fig. 5, partly in section, the scale being about as in Fig. 4.

Fig. 7 is a top plan view of a third form of this invention, enlarged as in Figure 5.

Fig. 8 is a fragmental perspective view of the 55

form shown in Fig. 7, partly in cross-section and enlarged as in Figure 6.

Fig. 9 is an enlarged fragmental top plan view of a fourth form of this invention.

Fig. 10 is a cross sectional view taken on the line 10—10 of Fig. 9, enlarged as in Fig. 3.

Fig. 11 is a fragmental perspective view of the device shown in Fig. 9, partly in cross-section and enlarged about like Fig. 10.

Fig. 12 is an enlarged fragmental top plan view of another (fifth) form of this invention.

Fig. 13 is a cross-sectional view taken on the line 13—13 of Fig. 12.

Fig. 14 is a fragmental perspective view, partly in cross-section, of the device shown in Figure 12 and also enlarged about as in Fig. 11.

Fig. 15 is a fragmental top plan view of another (sixth) form of this invention.

Fig. 16 is a cross-sectional view taken on the line 16—16 of Fig. 15 and enlarged like Figs. 3 and 10.

Fig. 17 is a fragmental perspective view of the device shown in Fig. 15 and also being enlarged like Figure 14.

Fig. 18 is an enlarged fragmental top plan view of another and seventh form of the present invention.

Fig. 19 is a cross-sectional view taken on the line 19—19 of Fig. 18.

Fig. 20 is an enlarged perspective view of the device shown in Figure 18, partly in cross section.

Referring in detail to the first form of my invention and especially to Figs. 1 to 4 of the drawings, my improved razor head 1 is seated in an elongated channel 2 formed in the upper end of a handle 3, wherein is housed the usual motor, not shown, and to which is attached a drive shaft 4, shown in dotted outline in Fig. 1. This shaft 4 extends through an aperture 5 in the lower part of the head 1 where it is connected to reciprocate a hollow cutter 6 slideable lengthwise within the guide chamber of the hollow shear head 1.

The thin top face part of head 1 is provided with a series of rows 7, 8, 9, and 10 of parallel narrow fixed shear cutters 11. The cutters of one row are staggered with respect to those in the next row, and each cutter is provided with a nearly vertical leading edge 12, and a dull tailing edge 12'. Each cutter 11 has a curved upper surface 11' so that the other edges are all tapered to a fine leading point 11''.

A cutter connecting web 13 extends across the middle part of the cutters for each of the rows. These webs are provided with tapered fore and

aft edges 13', the lines of which blend with the cutters to which they are integrally attached.

Each row of cutters is supported at the cutter ends by the upward flanges of channel strips 14, except that the outer ends of the outer cutters are carried by the side walls of the head.

When the shear head is drawn across the face of the object being shaved, the hairs are picked up by the leading edges 12 of the cutters. Then as the hairs slide along these tapered edges they are sheared off by the cross action of the movable cutter 6. If by any chance the hair is not sheared off by the time it reaches the web 13, it will again be straightened out at that point and probably sheared off. Should a hair escape being sheared off by the first row of cutters, it will be clipped off by some other cutter before the entire face of the shear head has passed over it, due to the sequential position and action of the cutters. The web 13 provides for positioning the hair vertically so that it may readily be sheared off close to the skin.

The novel cutter 6, here employed in reciprocating shear movement, comprises a series of channel-shaped members 15 arranged to seat around and coact with the channels 14. The cutter 6 is provided with a flat outer portion 16 comprising a series of four parallel face parts each of a width approximately that of the length of each of the cutters 11, and each face comprises a series of transverse shear elements. When these reciprocate under said cutters 11 they shear the hair.

In Figures 5 and 6, the second form of construction is substantially the same as that shown in the preferred embodiment with the exception that no web is employed between the cutters 11. In this case the upper edges 17 of the channel bars 18 act as the means to position a hair vertically, so that it may be sheared off close to the skin.

The modified construction shown in Figures 7 and 8 (third form) is substantially the same as that shown in Figs. 5 and 6, except that here the shear head is constructed so that the same may only be drawn across the face, in one direction for shearing action, whereas in the device of Figures 5 and 6 and in the preferred embodiment of Figures 1 to 4, the device is arranged to be drawn in both forward and backward directions.

In the constructions of Figures 7 and 8 the rear edges of the cutters 11 are provided with heels 19 and blend with and are formed integrally on the channel members 20.

In the form, shown by Figs. 9, 10 and 11, the shear head comprises a series of rows of cutters 21, alternate rows having their cutters inclined oppositely.

In this said construction, as in the preferred embodiment shown by Figures 1 to 4, a series of webs 26 and bars 23 are arranged lengthwise of the shear head to provide a means for raising the hairs to a vertical position so that they may be sheared.

The form of construction shown in Figs. 12, 13 and 14 has a head 22 formed with a relatively heavy center bar 24 and with two minor bars or webs 25 on each side. These bars and the sides 27 are all connected by rows of cutters 28 arranged staggerwise. The leading edges are shown at 29.

In the form of construction shown in Figures 15 and 16, each of the cutters 30 is provided with a leading edge which blends into the triangularly-

shaped bar 31 which takes the place of the bar 24 shown in Figures 13 and 14.

In the form of construction shown in Figures 18, 19 and 20 applicant has provided a series of criss-cross webs 32 forming a multiple diamond-shaped pattern. A channel bar 33 is provided in the medial portion of this shear head in order to give support for cutter webs 32; and the fore portion of a shear head 34 is provided with a series of leading edges 35 which blend into the diamond-shaped webs 32. This is also true of the aft portion of the head, wherein the diamond-shaped webs are provided with leading edges 36 which blend with the web. As will be apparent from the drawings, this shear head is adapted for effective movement in one direction only.

All of the forms herein shown provide a shear head which is designed to positively clip the hair with a minimum of effort. Each is designed to provide a means whereby hairs ordinarily not clipped by the mechanized razors now on the market will be brought to a vertical position on the face and actually sheared.

It is also to be noted herein that all of the movable cutters shown in the various modifications are specially designed to coact with the corresponding shear heads and are built to fit the same.

It is to be understood that some of the details set forth may be altered or omitted without departing from the spirit of the invention as defined by the appended claims.

I claim:

1. An elongated razor head adapted for shave movement crosswise thereof and comprising a face plate of shear cutter design in combination with a cutter plate also of shear design, the latter plate being reciprocable lengthwise of said head, said face plate comprising a plurality of parallel bars disposed lengthwise of said head and each having a series of shear cutters disposed crosswise thereon and in staggered relation to the corresponding cutters on the next adjacent bar or bars, and the second said plate having distinct cutter elements corresponding with and complementary to the several said cutters respectively on the said face plate, said cutters on said face plate having leading tips of wedge-shape with flared sides adapted to lift prostrate or recumbent hairs upwardly and into good cutting position, and said bars having between mutually adjacent cutters certain edge parts which are formed with backwardly inclined faces adapted to reach under recumbent hairs and lift them into better cutting position.

2. An elongated razor head adapted for shave movement crosswise thereof and comprising a face plate of shear cutter design in combination with a cutter plate also of shear design and, the latter plate being reciprocable lengthwise of said head, said face plate comprising a plurality of parallel bars disposed lengthwise of said head and each having a series of shear cutters disposed crosswise thereon and in staggered relation to the corresponding cutters on the next adjacent bar or bars and the second said plate having distinct cutter elements corresponding with and complementary to the several said cutters respectively on the said face plate, said cutters on said face plate having leading tips of wedge-shape with flared sides adapted to lift prostrate or recumbent hairs upwardly and into good cutting position.

NEIL HOLSCLAW.
